UNITED STATES PATENT OFFICE.

SAMUEL MILLER, OF HOMINY, OKLAHOMA, ASSIGNOR TO M. J. WESTBROOK, OF HOMINY, OKLAHOMA.

COMBINED WINDOW-SHADE AND CURTAIN-POLE HOLDER.

1,150,693.

Specification of Letters Patent.

Patented Aug. 17, 1915.

Application filed September 8, 1914. Serial No. 861,243.

To all whom it may concern:

Be it known that I, SAMUEL MILLER, a citizen of the United States, residing at Hominy, in the county of Osage and State 5 of Oklahoma, have invented certain new and useful Improvements in Combined Window-Shade and Curtain-Pole Holders, of which the following is a specification.

My invention relates to a combined window shade and curtain pole holder, and my 10 object is to provide a new and useful device of this character whereby a shade and a curtain may be lowered from the top of a window casing to admit air and light, and one 15 in which the shade and the curtain may be swung entirely to one side of said window casing, so that access may be readily had to the window glass for cleaning purposes.

In order that the invention may be fully 20 understood, reference will now be made to the accompanying drawing, in which:

Figure 1 is an elevation of the fixture applied to a window casing and showing in dotted lines how the shade and the curtain 25 pole are adjusted vertically. Fig. 2 is a broken plan view of the same, showing in dotted lines the manner in which the shade and the curtain pole may be swung away from the window. Fig. 3 is a broken side 30 elevation of the fixture applied to a window casing.

In carrying out my invention, I employ two brackets 1 and 2, the former being secured to the upper portion of the casing A, 35 and the latter a suitable distance below the former.

3 designates a rod extending vertically 40 through the brackets 1 and 2, in which it is adapted to slide vertically as indicated by the dotted lines, Fig. 1, and also rotate in a horizontal plane as indicated by the dotted lines, Fig. 2. Rod 3 is provided at its lower end with a handle 4, whereby it may be either adjusted vertically or rotated as 45 above described.

5 designates a coil spring interposed between the two arms of the bracket 2 and frictionally embracing the rod 3, to reliably hold the same at any point of its vertical adjustment.

6 designates a spring secured to the

bracket 1 and bearing firmly against the upper portion of the rod 3 to hold the same at any point of its rotative movement.

7 designates a sleeve secured to the upper 55 portion of the rod 3 by a pin 8, or other suitable means.

9 designates a curtain pole reliably secured to the sleeve 7 in any suitable manner. In the drawing I have shown the sleeve 7 60 provided with a laterally-extending, threaded stud 10, to engage internal threads in the adjacent end of the pole 9. Sleeve 7 is also provided with an arm 11 to coact with a corresponding arm 12 at the opposite end of the 65 pole 9, in supporting a shade roller B, one of said arms having a rectangular slot to receive the correspondingly shaped pin at one end of said shade roller, and the other arm having a circular hole to receive the trun- 70 nion at the opposite end of the shade roller.

When the upper window sash is lowered to admit air and light, the rod 3 is slid downward to the dotted position disclosed by Fig. 1, to lower the curtain pole and the 75 shade roller, so that the shade and the curtain which they carry will not obstruct the light nor the air entering the opening left by the upper sash. When it is desired to gain access to the entire window to wash the 80 same, or for any other purpose, the rod 3 is rotated to swing the curtain pole and the shade roller to one side, as indicated by the dotted lines, Fig. 2.

From the foregoing description it is ob- 85 vious that I have provided a simple and inexpensive fixture which is well adapted for the purpose intended, and while I have shown and described the preferred form of my invention, I reserve the right to make 90 such changes in the construction, proportion and arrangement of parts as properly fall within the spirit and scope of the claim.

Having thus described my invention, what I claim and desire to secure by Letters Pat- 95 ent, is:

A device of the class described comprising upper and lower brackets adapted to be secured to one side of a window frame, said lower bracket having a pair of horizontal 100 arms, vertically spaced, a single arm carried by the upper bracket, a vertical rod

slidably and rotatably supported by the arms of the brackets, a coil spring supported between the arms of the lower bracket and surrounding the rod, a pole supporting sleeve 5 fixed to the rod and adapted to engage the arm of the upper bracket and upper arm of the lower bracket to limit the vertical movement of said rod, said spring serving to fric-

tionally bind the rod to hold the same in adjusted positions. 10

In testimony whereof I affix my signature, in the presence of two witnesses.

SAMUEL MILLER.
